UNITED STATES PATENT OFFICE.

LEON BLOCH, OF NEW YORK, N. Y.

VALVE.

1,300,918.

Specification of Letters Patent. Patented Apr. 15, 1919.

Application filed May 24, 1918. Serial No. 236,367.

To all whom it may concern:

Be it known that I, LEON BLOCH, a citizen of the United States, residing at New York, in the county of New York and State of 5 New York, have invented new and useful Improvements in Valves, of which the following is a specification.

This invention relates to valves and particularly to globe valves for high pressure 10 use and it has for its primary object the provision of a valve chamber having a seat the opening through which is disposed substantially in line with the longitudinal center of the valve chamber whereby the steam will 15 be free for a continuous and straight passage through the chamber to be thereby held against being trapped in the chamber when the valve is opened; combining with the seat of the just stated character, a vertically movable stem and a valve suspended for universal movement from the stem and adapted to be wholly arranged above the opening in the seat when the valve is opened.

Another object of the invention is to provide 20 a valve including a chamber having a seat in which the opening therein is disposed substantially in a straight line with the longitudinal center of the chamber, and a valve which is adapted to assume a horizontal 25 position when opened and which is arranged and disposed to be canted through its initial contact with the valve seat and firmly positioned thereagainst to effect a perfect joint between the seat and valve when 30 the latter is seated.

With the above and other objects in view which will appear as the nature of the invention is better understood the same consists in the improved construction and novel 40 arrangements of parts which will hereinafter be fully described and particularly pointed out in the claim.

In the accompanying drawings, has been 45 illustrated, a single and preferred form of the invention, it being however understood that no limitations are necessarily made to the precise structural details therein exhibited, but that changes, alterations and modifications within the scope of the claim may 50 be resorted to when desired.

Figure 1 is a vertical section through the valve showing the same in an open position.

Fig. 2 is a side view thereof with parts in section, the valve being in a closed position.

55 Fig. 3 is a side view of the stem and valve body.

The valve consists of a chamber 5 having a diaphragm or wall 6 which is arranged at an angle other than a right angle to the longitudinal axis of the chamber and provided with a seat 7 whose opening 8 lies substantially in line with the longitudinal center of the valve chamber to permit of a direct straight passage of steam through the chamber when the valve is opened. Rising 60 from the chamber in vertical alinement with the opening through the diaphragm or wall 6 is a threaded collar 9 which receives a correspondingly threaded bonnet or support 10 for a vertically adjustable valve stem 11, 70 the same having a thread 12 which is received in threaded bore 13 in the support in order that the valve can be moved up and down and satisfactorily held in the desired position. The support 10, when removed 75 from the collar 9 uncovers the interior of the collar in order that a suitable grinding tool may be advanced against and operated over the seat 7 as will be appreciated on reference to Fig. 1, wherein such relative association of parts is made so as to permit this functioning of the elements. The support 10 is provided with a suitable packing gland 14 which is arranged to establish a steam tight joint against the valve stem. 80

The lower end of the valve stem is provided with a ball section 15 with which is associated a socket section 16. This socket section is threadedly connected at 17 with a base member 18 which is cupped at 19 for 90 the reception of a valve disk 20. Interposed between the ball section 15 of the valve stem and the member 18 is a spherical body 21 which is designed to permit the base member 18 to move universally from the valve stem. 95 The disk 20 can be constructed of any desired material according to the various uses to which the valve may be placed. The base section 18 is provided with a threaded stem 22 which passes through the disk 20 and beneath the disk said stem is connected with an adjusting nut 23 which may be adjusted against the disk to firmly hold the same in the cupped portion 19 of said base section 18. This construction provides a flexible 105 connection for the disk 20 so that the latter can be freely canted.

The valve stem is positioned with respect to the valve seat so that movement of the former will be interrupted or arrested by the 110 position of the latter. When the valve is opened as shown in Fig. 1 the disk 20 gravi-

tationally assumes a horizontal position. A movement of the valve stem in the direction of the seat 7 causes the disk 20 to strike against the highest point of the valve seat 5 and as pressure is continued against the disk by rotating the stem 11, the valve disk is canted and thereby made to fully contact with the seat as shown in Fig. 2. It will be observed that through this arrangement 10 when the valve disk is opened as shown in Fig. 1, it is disposed above the highest point of the valve opening so as to provide, in combination with the position of the valve opening, a perfect free passage for the discharge of steam through the valve chamber. 15

In order to permit the valve disk to assume such position, the member 10 is chambered at 24 to accommodate the disk.

What is claimed as new is:—

A valve structure comprising a chamber 20 member having a valve seat, a stem movable relatively to the seat, and a flexibly connected valve disk supported from said stem, the seat being arranged to intercept the path of movement of the disk and adapted to 25 effect a canting action of the disk against the seat when the stem is moved toward the seat.

In testimony wherof I affix my signature.

LEON BLOCH.
